(57) **CLAIM**

The ornamental design for a latch assembly having a spring clip, as shown and described.

DESCRIPTION

FIG. 1 is a perspective view of a latch assembly having a spring clip showing my new design;

FIG. 2 is a top plan view thereof;

FIG. 3 is a front elevational view thereof;

FIG. 4 is an enlarged scale right side elevational view thereof;

FIG. 5 is a rear elevational view thereof;

FIG. 6 is an enlarged scale left side elevational view thereof;

FIG. 7 is a bottom plan view thereof;

FIG. 8 is a perspective view of a second embodiment of a latch assembly having a spring clip;

FIG. 9 is a top plan view of FIG. 8;

FIG. 10 is a front elevational view of FIG. 8; and,

FIG. 11 is a right side elevational view of FIG. 8.
